UNITED STATES PATENT OFFICE.

GEORGE W. ENGLE, OF CANTON, SOUTH DAKOTA.

CROSSING-GRADE.

1,035,695.

Specification of Letters Patent. Patented Aug. 13, 1912.

Application filed July 11, 1910. Serial No. 571,399.

To all whom it may concern:

Be it known that I, GEORGE W. ENGLE, a citizen of the United States, residing at Canton, in the county of Lincoln and State of South Dakota, have invented a new and useful Crossing-Grate, of which the following is a specification.

The grate which is the subject of the present invention is designed for use at street crossings between the side walk and the end of the crossing, to cover the water conduit or gutter; and it is the object of the invention to provide a grate of this kind which is simple, cheap and durable, and by the use of which the conduit can be easily cleaned, and kept in working order.

In the accompanying drawing forming a part of this specification, Figure 1 is a plan view of the grate. Fig. 2 is an enlarged cross section on the line 2—2 of Fig. 1. Fig. 3 is an enlarged section on the line 3—3 of Fig. 1.

As shown in the drawing, the grate is composed of a series of parallel channel bars 5 which are fastened together in spaced relation by end angle bars 6, and a bottom center cross bar 7. The bars 6 are arranged so that one of the flanges thereof stands perpendicular and the other horizontal, the perpendicular flanges extending across the ends of the bars 5, and the horizontal flanges being located at the bottom of the grating. The tops of the perpendicular flanges are flush with the tops of the bars 5. The bars 5 are arranged so that their flanges extend perpendicularly and downwardly, said bars extending at their ends into the angles of the bars 6. By this construction a grate is had which is strong and durable, and smooth on top.

The bars 5 and 6 are fastened together by rivets, bolts or other suitable fastening means 8 which pass through the horizontal flanges of the bars 6, and through the webs 45 of the bars 5. Similar fastening means 9 pass through the center cross bar 7 and the webs of the bars 5. The fastening means at the end of each row thereof are fitted with sleeves 10 which are located in the channels 50 of the bars 5 between the webs thereof and

the horizontal flanges of the bars 6. Similar sleeves are placed around the fastening means 9 at the center of the row. These sleeves are provided to prevent the side thrust, occasioned by persons walking on 55 the grating, from gradually pushing the outside edges of the bars 5 off the end and center cross bars, and letting the same down, it being an inevitable conclusion from the foregoing that the terminal bars 5 have 60 limited sliding movement upon the angle bars 6. Owing to the movement of which the terminal bars 5 are capable, the grate will expand and contract to accommodate 65 the expansion and contraction of the structure in which the grate is mounted.

The grate herein described is light, strong and durable, it being made entirely of steel. By its use, the conduit for surface water can be easily cleaned and kept in working 70 order, and the conduit under the crossing thaws out just as soon as the street gutter, and is always open and visible for inspection.

What is claimed is:

A crossing grate comprising spaced channel bars having their channels downwardly presented; angle bars receiving the ends of the channel bars; securing elements engaging the channel bars and the angle bars; 80 and sleeves surrounding the securing elements and terminally engaged by the angle bars; the terminal channel bars being slideable upon the angle bars to provide for expansion and contraction in the grate, to accommodate the expansion and contraction of the structure in which the grate is mounted, the sleeves constituting means for supporting the terminal channel bars when 85 the outer flanges thereof are advanced beyond the ends of the angle bars by foot thrust.

In testimony that I claim the foregoing as my own, I have hereunto affixed my signature in the presence of two witnesses.

GEORGE W. ENGLE.
